Geo. Himmel

ATTORNEY.

UNITED STATES PATENT OFFICE.

MAX EMIL TOBELE, OF DETROIT, MICHIGAN:

REMOVABLE TOOL HOLDER.

Application filed January 24, 1928. Serial No. 249,094.

This invention relates to a tool holder and more particularly to the class of removable tool holders.

The primary object of the invention is to provide a chuck or tool holder used in connection with punch presses and similar machines, wherein the tool will be firmly and securely held fast therein and it can be conveniently and readily removed when occasion 10 requires, in event that the said tool becomes worn, broken or otherwise damaged, rendering it unfit for further service.

Another object of the invention is to provide, in a manner as hereinafter described a 15 chuck or tool holder of the character described provided with a key to prevent movement of the tool while in use, and further provided with both an automatic and positive locking means to prevent the key from movement within its seat.

A further object of the invention is to provide, in a manner as hereinafter set forth a chuck or tool holder of this character, which is extremely simple in construction, thoroughly reliable and efficient in its purpose, 25 strong, durable, readily and easily accessible for the release of the tool held therein, and inexpensive to manufacture and install.

With the foregoing and other objects in view, the invention consists of the novel construction, combination and arrangement of parts as hereinafter more specifically described and illustrated in the accompanying drawings, wherein is shown an embodiment 35 of the invention, but it is to be understood that changes, variations and modifications may be resorted to which fall within the scope of the claim hereunto appended.

In the drawings wherein like reference 40 characters denote corresponding parts throughout the several views:—

Figure 1 is a vertical sectional view in accordance with this invention, through the chuck or holder showing the tool assembled 45 therein.

Figure 2 is a top plan view of the chuck or tool holder.

Referring to the drawings in detail A represents a portion of the punching press or other machine, to which the chuck or tool holder is attached in any desirable manner. B represents the die of the punching press and C illustrates a piece of material being perforated.

The chuck or tool holder comprises a cylind-

rical body 3 although the shape thereof may be varied at the option of the maker. Furthermore the size of body 3 may be varied and it may be made of any suitable material. Extending through and formed centrally in 60 the body 3 is a tool socket 4 within which is removably seated the tool 5, said tool being locked therein for removability as herein-after described.

Eccentrically arranged with respect to the 65 socket 4, in the body 3, is a circular cavity 6 extending through the major portion thereof and opening through one face of the body 3, while its opposite end merges into an aperture or passage 7 of considerably less diameter than the cavity 6. The aperture or passage 7 opens through the opposite face which may be termed the lower face of the body 3 of the tool holder. Movable confined within the cavity 6 is a plunger 8 the same being 70 acted upon by an expansion spring 9 one end of which abuts against the plunger and the other end against the machine A. The pressure exerted upon the plunger 8 by the spring automatically retains a key 11, within its seat 80 as will be clearly understood from Figure 1 of the drawings.

The plunger 8 is provided with a cut-away portion or slot 10 on the circumferential face thereof, and said cut-away portion extends longitudinally from the lower plane face of said plunger a length slightly less than the diameter of the key 11, and less than the length of the plunger. The cut-away portion 10 confines the cylindrical key 11 90 and said cut-away portion terminates at its upper end in a shoulder the shape of which conforms to the shape of the key, so that a tight contact results when the key and shoulder abut by the pressure exerted by the spring 95 or by the positive adjustment hereinafter to be described.

Extending longitudinally through the walls from the top to the lower face of the plunger 8, and registering with the aperture 7 of the body 3, is a threaded opening 12. The screw 13 passes through the aperture 7 and engages the threaded opening 12 of the plunger. In punching heavy material it is necessary to exert greater pressure on the 105 key than is derived from the spring. By turning the screw 13 the plunger 8 is moved downwardly until the shoulder of the cut-away portion 10 engages and locks the key 11 to the tool 5. The top face of the plunger 110

8 is provided with a centrally disposed stop lug 8' which positively limits the upward movement of the plunger by abutting against the machine A, so that it will be impossible 5 for the key 11 to be so displaced from its seat as to become jammed under the plunger 8.

The wall between the socket 4 and the cavity 6 is provided with a slot 14, extending 10 the length of the cavity 6, through which the inner half of key 11 projects. Registering with slot 14 at the lower end thereof is a semicircular key-way 15 cut transversely across the shank of the tool to engage the 15 inner half of key 11.

The tool 5 is provided with an opening 17

below the socket and extending transversely through its walls for the purpose of inserting a bar to pry the tool from the chuck or holder in event the tool becomes jammed. 20

What I claim is:—

A tool holder provided with a key for securing a tool in the tool socket of said holder, a plunger frictionally engaging said key for automatically retaining the key in engaged position, and adjustable means threadably engaging in the plunger and extending lengthwise of the tool socket for locking said plunger in key engaging position. 25

In testimony whereof, I affix my signature 30 hereto.

MAX EMIL TOBELEER.
